US00D841684S

(12) **United States Design Patent** (10) **Patent No.:** **US D841,684 S**
(45) **Date of Patent:** **** Feb. 26, 2019**

(54) **DISPLAY SCREEN OR PORTION THEREOF
WITH GRAPHICAL USER INTERFACE**

(71) Applicant: **Apple Inc.**, Cupertino, CA (US)

(72) Inventor: **Raymond Sepulveda**, San Jose, CA (US)

(73) Assignee: **Apple Inc.**, Cupertino, CA (US)

(***) Term: **15 Years**

(21) Appl. No.: **29/646,083**

(22) Filed: **May 1, 2018**

Related U.S. Application Data

(63) Continuation of application No. 29/582,383, filed on Oct. 27, 2016, now Pat. No. Des. 820,304.

(51) **LOC (11) Cl.** **14-04**

(52) **U.S. Cl.**

USPC **D14/487**; D14/490; D14/491; D14/492

(57) **CLAIM**

The ornamental design for a display screen or portion thereof with graphical user interface, as shown and described.

DESCRIPTION

The sole FIGURE is a display screen or portion thereof with graphical user interface showing my new design.

The peripheral dashed broken lines illustrate a display screen or portion thereof, and form no part of the claimed design.

1 Claim, 1 Drawing Sheet
